Primary Examiner — Jack Reickel*Assistant Examiner* — Michael A Kervin*(74) Attorney, Agent, or Firm* — Justin D. Swindells; Ice Miller LLP(57) **CLAIM**

The ornamental design for a light stake as shown and described.

DESCRIPTION

FIG. 1 is a front perspective view of a light stake.

FIG. 2 is a back perspective view of the light stake shown in FIG. 1.

FIG. 3 is front view of the light stake shown in FIG. 1.

FIG. 4 is a back view of the light stake shown in FIG. 1.

FIG. 5 is a left view of the light stake shown in FIG. 1.

FIG. 6 is a right view of the light stake shown in FIG. 1.

FIG. 7 is a top view of the light stake shown in FIG. 1; and, FIG. 8 is a bottom view of the light stake shown in FIG. 1. The broken line showing of a light stake is for purpose of illustrating portions of the article and forms no part of the claimed design.
